UNITED STATES PATENT OFFICE.

FREDERIC HENRY PUTNAM, OF BOSTON, MASSACHUSETTS.

DESIGN FOR A MEDICINAL TABLET AND PELLOID BOX.

No. 37,760.

Specification for Design.

Patented Dec. 26, 1905.

Application filed November 16, 1905. Serial No. 287,742. Term of patent 14 years.

To all whom it may concern:

Be it known that I, FREDERIC HENRY PUTNAM, a citizen of the United States, residing at Boston, in the county of Suffolk and State of Massachusetts, have invented a new, original, and ornamental Design for Medicinal Tablet and Pelloid Boxes, of which the following is a specification, reference being had to the accompanying drawings, forming part thereof.

Figures 1 and 2 of the drawings represent, respectively, obverse and reverse perspective views of my design.

I claim—

The ornamental design for a medicinal tablet and pelloid box as shown.

FREDERIC HENRY PUTNAM.
